(57) **CLAIM**

The ornamental design for a shower pan, substantially as shown and described.

DESCRIPTION

FIG. 1 is a perspective view of an embodiment of the shower pan;
FIG. 2 is a right side elevational view of the shower pan of FIG. 1;
FIG. 3 is a top plan view of the shower pan of FIG. 1;
FIG. 4 is a rear view of the shower pan of FIG. 1;
FIG. 5 is a left side elevational view of the shower pan of FIG. 1;
FIG. 6 is a front view of the shower pan of FIG. 1; and,
FIG. 7 is a bottom plan view of the shower pan of FIG. 1.
The broken line rendering of portions of the article, defined with dashed lines, is included for the purpose of illustrating environmental structure and forms no part of the claimed design.

1 Claim, 2 Drawing Sheets
